THE NORRIS PETERS CO., WASHINGTON, D. C.

UNITED STATES PATENT OFFICE.

CHARLES S. BARON AND JAMES F. HAFFEY, OF TIFFIN, OHIO.

RECEPTACLE.

981,239.

Specification of Letters Patent. Patented Jan. 10, 1911.

Application filed April 26, 1910. Serial No. 557,647.

To all whom it may concern:

Be it known that we, CHARLES S. BARON and JAMES F. HAFFEY, citizens of the United States, residing at Tiffin, in the county of Seneca, State of Ohio, have invented a new and useful Receptacle, of which the following is a specification.

It is the object of this invention to provide a device adapted to contain salt, talcum powder, and the like, the construction of the device being such that the cap and the body proper, although held securely together may, nevertheless, be readily separated.

Another object of the invention is to provide a spring locking device of novel and improved form, adapted to hold together the cap and the body of a device of the character hereinafter described.

Another object of the invention is to provide a cap and a body, having elements which are adapted to be engaged by a spring locking device.

In the drawings,—Figure 1 shows the invention in perspective; Fig. 2 is a top plan of the showing of Fig. 1; Fig. 3 is a transverse section upon the line A—B of Fig. 2; Fig. 4 is a transverse section upon C—D of Fig. 2; Fig. 5 is a top plan of a modification; Fig. 6 is a transverse section E—F of Fig. 5; Fig. 7 is a top plan of a modification of the invention; Fig. 8 is a transverse section on G—H of Fig. 7; and Fig. 9 is a detail perspective setting forth a modification in the cap.

The body of the device is denoted by the numeral 1, and has, upon its interior, an outstanding shoulder 2, upon which the cap 3 is adapted to rest, within the contour of the body. The cap 3 is surrounded by an outstanding shoulder 4, having oppositely disposed notches 5 therein. In the body 1, adjacent its upper end, there are open marginal seats 6, adapted to be brought into alinement with the notches 5 in the cap 3. The upper end of the body 1 is surrounded by a groove 7. A spring strip 8 is shown, the ends of which are inwardly bent to form fingers 9, and these fingers 9 are inserted in the body 1, within the contour of the groove 7 therein, so that the arcuate spring strip 8 is hingedly connected with the body 1. There are inwardly extended projections 10, formed by bending the spring strip 8, and these projections 10 of the

spring strip 8 are adapted, when the spring

strip is swung over so as to interlock with the groove 7, to fit in the notches 5, thus holding the cap 3 in place, both against dropping from the body 1, and against rotation therein.

If desired, the cap may be modified to the extent indicated in the form denoted by the numeral 11. In this cap 11, there are oppositely disposed notches 12, forming shoulders 14 in the cap. In this form of the invention, the spring strip 20 surrounds the body 1 entirely, the ends 15 of the spring strip being spaced slightly apart, to permit the strip to be sprung over the top of the body, to register in the groove 7 therein. The projections 10 interlock in the notches 12 of the cap 11, the shoulders 14 co-operating with the projections, prevent the cap from being shaken out of the body. Likewise, the cap is prevented from rotating in the body.

If desired, the spring may take the form denoted by the numeral 16, the same being a semi-circular structure, the ends of which are bent into co-axial relation, to extend toward each other, thus forming fingers 17, adapted to extend through the open marginal seats 6, to hold the cap 3 in place.

Obviously, any of the common materials of construction may be employed for fashioning the body 1 and the cap 3; and many changes, properly falling within the scope of what is claimed, may be made, without departing from the spirit of the invention or sacrificing any of the advantages thereof.

It is of course obvious that there may be no notches in the cap to receive the protruding fingers of the attaching spring. Such a cap 31, provided only with the outstanding shoulder 4, is shown in Figs. 7 and 8. Furthermore, the cap denoted by the numeral 30 in Fig. 9, may be employed, the cap being merely a flat disk, within the contour of the upper face of which the inwardly extended fingers of the spring locking device are adapted to extend, the cap resting upon the shoulder 2.

Having thus described the invention, what is claimed is:—

1. A device of the class described comprising a body; a cap therein; and a spring embracing the outside of the body and having spaced projections extended toward each other through open marginal seats in the body to engage the cap.

2. A device of the class described comprising a body having a shoulder in its interior; a cap to rest upon the shoulder; and a spring embracing the outside of the body 5 and having spaced projections extended toward each other through open marginal seats in the body to overhang the cap.

In testimony that we claim the foregoing

as our own, we have hereto affixed our signatures in the presence of two witnesses.

CHARLES S. BARON.
JAMES F. HAFFEY.
